Patented Dec. 16, 1969

216,307

PHARMACEUTICAL TABLET

Fred C. Ninger, Livingston, N.J., assignor to Warner-Lambert Pharmaceutical Company, Morris Plains, N.J., a corporation of Delaware

Filed Apr. 22, 1969, Ser. No. 16,851

Term of patent 14 years

Int. Cl. D28—01; D1—02
U.S. Cl. D16—3

FIG. 1 is a view in perspective of a pharmaceutical tablet embodying my new design;

FIG. 2 is a top plan view thereof;

FIG. 3 is a side-elevational view thereof;

FIG. 4 is an end view thereof, taken 90° from the side view of FIG. 3.

I claim:

The ornamental design for a pharmaceutical tablet, substantially as shown.
